GARBAGE DISINFECTING DEVICE

Louis Schneider and Najam Modad,
Carbondale, Pa.

Application June 28, 1935, Serial No. 28,948

3 Claims. (Cl. 220—87)

The present invention relates to an improvement in the garbage disinfecting device disclosed and claimed in the applicants' prior Patent, No. 1,928,864.

More specifically, the present invention has particular relation to a garbage can attachment of the general character of the device of the aforesaid prior patent, but wherein the number of parts has been substantially reduced without impairing the efficiency and practicability of the attachment, and wherein the improved device is more readily manipulable and more easily and inexpensively manufacturable.

The desirability of garbage disinfecting devices of the character here involved, which are adapted to contain and to disseminate suitable disinfecting chemical vapors or the like whereby breeding of flies and similar health-endangering vermin is effectually prevented, is obvious. As a matter of fact, the Public Health Service of the United States is constantly conducting a campaign intended to educate the population in the use of such fly-destroying devices.

According to the present invention, an improved device is provided whereby the construction and mode of operation of applicants' prior device are appreciably simplified without prejudicing the several advantages obtained by the latter and, as a matter of fact, adding to such advantages.

Thus, the device according to the present application may be readily associated with garbage cans of standard construction and conventional form, such as are now available on the market. In addition, slight modification of a part of such standard constructions may enable such part to effect the function of an element of the attachment embodiment of the invention, whereby the latter is further appreciably simplified.

As in the previous arrangement, the device according to the present invention may be mounted, without involving the use of tools other than those commonly available in the ordinary home, at various locations on the garbage can, such as the top, side, or bottom thereof, depending upon the character of the specific disinfecting agent employed, as will appear more clearly from the detailed description of the invention hereinafter set forth.

The foregoing and other objects and advantages of the present invention will be readily apparent to those skilled in the art to which the present invention pertains from the following disclosure thereof. Applicants' novel and improved relationships of parts are set forth in detail in

the following description, which will be better understood by reference to the accompanying drawing, illustrating several embodiments of the invention.

Similar reference characters designate corresponding parts throughout the several figures of drawing, of which:

Fig. 1 is a view, partly in elevation and partly in section, of a part of a garbage can in which the present invention has been incorporated; . . . 10

Fig. 2 is a view of the attachment unit per se, as seen in the direction of arrow A of Fig. 1;

Fig. 3 is a sectional view taken substantially along line 3—3 of Fig. 2;

Fig. 4 is a detached view of the disinfectant container per se, according to the present invention; and

Fig. 5 is a sectional view showing a modified embodiment of the invention in connection with the cover of a garbage can.

Reference numeral 10 designates a conventional construction of garbage can which is closed at the top by a manually removable flanged cover 11 provided with the usual handgrip 12. A suitable articulated handle member 13 for carrying the can about is shown at 13. It will be understood, of course, that the garbage can may also assume the form shown in applicants' prior patent, aforementioned, or any other suitable or desired form.

In the arrangement of parts illustrated in Fig. 1, the garbage disinfecting device, which constitutes the present invention proper, is shown as attached to the side wall of can 10. It will be understood, in this regard, that the device may also be attached, in analogous manner, to the cover or bottom of the can, depending upon the specific type of disinfecting chemical employed. Thus, if the disinfectant agent is of a type which evolves vapors heavier than air, the attachment is preferably arranged to depend from the cover. If, on the other hand, vapors materially lighter than air are evolved, it may be preferred to mount the attachment on the inner surface of the can bottom. An advantage of positioning the attachment on the side wall of the can intermediate the top and bottom thereof is that a better permeation of the disinfectant vapors through the garbage mass is obtained.

In the embodiment shown in Figs. 1, 2 and 3, 50 the garbage disinfecting device or attachment comprises a base plate or mounting plate or supporting plate 14 and a coacting disinfectant container or receptacle 15.

The base or mounting plate 14 is preferably 55

of the configuration clearly shown in Fig. 2 of the drawing, that is, it comprises a substantially circular central portion 16 provided with diametrically opposite tonguelike extensions 17. The central portion 16 is preferably somewhat larger than the top or open end of container 15, whereby it may constitute a closure for such open end. Tonguelike extensions 17 are preferably perforated for the passage of suitable threaded attaching bolts 18.

Plate 14 may be readily stamped out from suitable sheet metal, and by employing a suitable die, an intermediate portion 19 of the plate may simultaneously be displaced from the body of the plate, as shown in Figs. 2 and 3, to form a tongue-receiving slot or opening 20.

The disinfectant container 15 is preferably dish-shaped, as shown on the drawing, and is preferably provided at its upper edge (i. e., the opening defining edge) with a bent-over flange 21 which extends entirely therearound except as hereinafter set forth. Intermediate the top and bottom thereof, the wall of the container 15 is provided with a plurality of perforations 22, substantially as illustrated. The other terminal end or bottom 23 of the container is imperforate. Bottom 23 is preferably connected to the main wall of the container by an outwardly flared portion 24. This arrangement provides a shoulder or groove adjacent the bottom 23 which affords a convenient means whereby the container 15 may be grasped by the manipulator's fingers during mounting on or removal thereof from the can. Container 15 is preferably constructed of relatively heavy gauge metal whereby it is well adapted to resist any possible crushing forces due to packing of the refuse or the like.

At one point along the extent thereof, bent-over flange 21 is deformed to provide outwardly extending tongue member 25 which, as shown on the drawing, also extends slightly upwardly. At a diametrically opposite point, flange 21 merges into extension 26 which, as shown more particularly in Fig. 3, may be somewhat offset to impart resilience thereto. Extension 26 is preferably slotted as at 27 (Fig. 2) to receive the corresponding attaching bolt 18.

As shown on the drawing, container 15 is associated with its mounting plate or support 14 by slipping tongue 25 into slot 20 and by disposing slot 27 on the corresponding bolt 18. Wing nuts 28 are mounted on bolts 18 for retaining the parts in place. A nut 29 may be arranged on bolt 18 between plate 14 and extension 26 to retain the plate in place notwithstanding removal of the corresponding wing nut 28 upon removal of container 15 for refilling or other purposes. Nut 29 is particularly useful in the event this embodiment of the invention is mounted in depending relationship from the top or cover of the can.

In the embodiment shown in Fig. 5, mounting plate 14 is omitted and the function thereof is effected by the garbage can cover 30. To this end, the latter is, of course, provided with a slot 20' adapted to receive tongue 25. Elimination

of mounting plate 14 also involves elimination of the particular retaining means set forth in connection with the aforescribed embodiment of the invention. In the embodiment according to Fig. 5, extension 26 is replaced by an unslotted extension 26' provided with a terminal bead 26''. A suitably bent spring plate 31 is provided on the interior of cover 30, and extension 26' and its bead 26'' coact with the said spring plate to releasably retain the attachment in place.

Any desirable or suitable form of disinfectant material may be disposed in container 15. This material is indicated diagrammatically in broken lines at 32. If solid, it is placed directly within container 15; if liquid, it may be applied to waste 15 or the like which is then placed in the container. If powdered, it may be enclosed within a textile bag or the like which is then disposed in the container. The chemical vapors evolved from the disinfectant material pass into the interior of the garbage can through the openings in the wall of the container. Although preferred details of the invention have been described at some length, it is not thereby intended to limit the scope of the invention or otherwise than by the terms of the claims hereunto appended.

Having disclosed the invention, what is claimed is:

1. An attachment of the character described, particularly adapted for use with conventional garbage can constructions, said attachment comprising a base plate, bolt-and-nut means for attaching said plate to said can construction, a disinfectant container adapted to be releasably mounted on said base plate, said base plate being deformed to provide a tongue-receiving opening therein and said container being provided with a projecting tongue adapted to be arranged in said opening when said container is in mounted position, and means for retaining said container in mounted position while permitting ready dismounting thereof.

2. The construction defined in claim 1, said last-named means comprising a slotted tongue extending from said container, said slotted tongue being operatively associated with a portion of said bolt-and-nut means, one bolt of the latter passing through said slot.

3. An attachment of the character described comprising a base plate, means for attaching said plate to said can construction, a disinfectant container adapted to be releasably mounted on said base plate, said base plate being deformed to provide a slot and said container being provided with a projecting tongue adapted to be received in said slot when said container is in mounted position, and means for retaining said container in mounted position while permitting ready dismounting thereof, said container comprising a perforated peripheral wall and an imperforate end, said wall being deformed adjacent said end to provide a readily-manipulable shoulder, whereby the attachment may be conveniently held while mounting or dismounting it.
